UNITED STATES PATENT OFFICE

2,413,717

FLUID SYSTEM

Howard J. Kerr, Westfield, N. J., assignor to The Babcock & Wilcox Company, Jersey City, N. J., a corporation of New Jersey

Original application April 30, 1938, Serial No. 205,229. Divided and this application July 11, 1942, Serial No. 450,546

2 Claims. (Cl. 122—459)

1

This invention relates to improvements in steam generators, and more particularly to methods and means for the production of high quality steam in a steam generator. The invention involves the washing of generated steam, and the utilization of feed water at high velocity to effect or accelerate the positive separation of steam and water after the washing of the steam.

The invention provides apparatus including a centrifugally acting steam and water separator in which the separation of steam and water is accelerated by the introduction of feed water to the whirl chamber of the separator in a substantially tangential direction, and in such a way as to induce a higher velocity of tangential steam flow into the whirl chamber.

Other objects of the invention will appear as the following description proceeds.

The invention will be described with reference to the accompanying drawing in which a preferred embodiment is illustrated.

In the drawing:

Fig. 1 is a vertical section through a steam and water drum equipped with a centrifugal steam separator and steam washer;

Fig. 2 is an enlarged view of the centrifugal separator and steam washer used in the drum shown in Fig. 1;

Fig. 3 is an elevation of the Fig. 1 centrifugal separator and steam washer taken at right-angles to the elevation shown in Fig. 2;

Fig. 4 is a plan of the Fig. 3 centrifugal separator and steam washer, looking upwardly as indicated by the arrow at the bottom of Fig. 3.

Fig. 1 of the drawing shows the steam and water drum which is intended to be the steam offtake drum of the steam generator. It is intended to occupy a position similar to that of the drum 12 in Fig. 1 of applicant's Patent 2,289,969 which issued on July 14, 1942, upon the parent application, Serial Number 205,229, filed April 30, 1938, of which this application is a division. This drum is connected by steam circulators 172 to a forwardly disposed drum, and it is connected to a submerged drum by the water tubes 174. Feedwater is supplied to the drum 170 through the tubular member 176 which is connected with a plurality of upwardly extending tubes 180 having nozzles 182 discharging into the tangential inlets 184 of the combined steam separators and steam washers 186. These inlets are in communication with the steam space of the drum 170 so that steam and water mixtures enter the washers 186 tangentially at high velocity. The separated steam is discharged axially of the washers

186 and upwardly through the steam offtake tubes 190 to a superheater or a point of use. Water is discharged tangentially outwardly of the combined separators and washers 186 through the outlets 192 and into the drum 170.

From an inspection of Figs. 1 to 4, inclusive, it will be noted that the inlet opening of each nozzle 184 is disposed in the upper part of the steam space of the drum 170 and that it opens downwardly toward the water space of the drum. With this arrangement the steam flow entering the nozzle 184 takes place, to a considerable extent, upwardly past an outlet 192. The latter is formed as a nozzle with a flattened outlet end as clearly indicated in Fig. 3. Thus, water of less concentration separated from the steam in the whirl chamber 186 is directed in a flat wide stream in intersecting relation to the flow of steam into a nozzle 184. In addition to this washing effect, the position of the feed water nozzle 182 centrally of the inlet 184 (as clearly indicated in Fig. 2 of the drawing) not only causes an increase in velocity of the whirling fluid within the whirl chamber 186, but it also acts to cause considerable mixing of the feed water and steam in the inlet 184 before the whirl chamber is reached. Thus, in effect, each combined steam washer and whirl chamber 186 effects two stages of steam washing.

I claim:

1. In a steam generator, a steam and water drum having a water level therein, means whereby a steam and water mixture enters the drum, means forming the whirl chamber of a combined steam washer and steam and water separator disposed in the steam space of the drum, means forming a steam offtake leading from the drum, the whirl chamber having a separated steam outlet directly connected to said offtake, means forming a primary whirl chamber steam and water inlet tangentially arranged with reference to the whirl chamber and receiving steam flow from the drum steam space, a feed water nozzle directly communicating with a source of relatively pure feed water and directing the feed water to the whirl chamber through the primary inlet, and nozzle means forming a restricted whirl chamber outlet for separated water, said nozzle means having its outlet part directed transversely to the direction of steam flow into the primary inlet so as to direct the separated water from the whirl chamber into intersecting relation to the flow of steam into the whirl chamber inlet.

2. In a steam generator, a steam and water

drum having a water level therein, means forming a steam offtake for said drum, means whereby steam and water mixtures enter the drum, means forming the whirl chamber of a centrifugal steam and water separator disposed within the steam space of the drum, means forming a whirl chamber steam inlet open to the steam space of the drum and directing the incoming fluid substantially tangentially into the whirl chamber, means whereby relatively pure feed water is discharged 10 in a jet within the said whirl chamber inlet and

directed tangentially into the whirl chamber along with the steam, the steam entering the whirl chamber mixing with the feed water as the latter enters the whirl chamber, and a nozzle forming a restricted whirl chamber outlet for separated water, said nozzle being disposed transversely of the flow into the whirl chamber steam inlet so as to direct the separated water across the flow of steam into the whirl chamber steam inlet.

HOWARD J. KERR.
